SHOE AND METHOD OF MAKING SAME

John E. Disch, Dolgeville, N. Y., assignor to
 Daniel Green Company, Dolgeville, N. Y., a
 corporation of Massachusetts

Application December 9, 1937, Serial No. 178,859

8 Claims. (Cl. 12—142)

My invention relates generally to footwear, and more particularly to a novel type of women's slippers known as mules, and more especially to the heel and sole structure thereof and methods 5 of forming such heel and sole.

The objects of my invention are, among other things, to provide a novel and improved heel and sole construction in slippers of this type whereby the edge of the sole is drawn under the 10 heel and there secured to furnish a finished even outline around the heel; also a novel form of slipper in which the sole padding extends under the heel and is secured thereto by the margin of the heel cover that is superposed over and cemented to the sole padding to secure an even 15 outline; also a slipper having its heel cover cemented to the shank portion of the sole padding with that portion of the upper adjacent to the shank extending inwardly over the shank portion 20 of the sole padding and cemented thereto, by which additional supports are given to the shank of the slipper.

Further objects of my invention also include a novel form of slipper heel construction which 25 embodies a cushion or padding both on the top and bottom of the heel that make such slipper both noiseless and comfortable when worn even though a hard heel is used; also to provide a slipper having a heel that is cupped or hollowed 30 out to permit the cushion or padded insole or sock lining to form a depression for the heel of the foot thereby preventing the slipper heel from running over when the slipper is worn.

A further object of my invention is to provide 35 an exceptionally simple but highly effective and long-wearing slipper heel construction which may be economically manufactured and which will retain its proper shape and contour in use.

Other objects and advantages will appear from 40 the following description when taken with the annexed drawing in which:

Fig. 1 is a top plan view of the type of slipper 45 embodying my improved heel and sole construction;

Fig. 2 is a side elevation of the heel and shank portion;

Fig. 3 is a top plan view of the heel portion 50 illustrated in Fig. 2 and showing the assembling of the parts in the first step in forming the heel;

Figs. 4, 5 and 6 are detail sectional views showing the successive steps in uniting the parts in forming the heel from Fig. 3 to Fig. 7;

Fig. 7 is a top plan view, partly broken away, 55 to show the position of the parts forming the

heel after the margin of the heel cover is cemented to the shank;

Fig. 8 is a sectional view of Fig. 7 but having the sock lining or inner sole cemented to the heel; and

Fig. 9 is a plan view of the heel and shank portion of the slipper as shown in Fig. 1, but broken away at portions to show the arrangement and union of the parts beneath the inner sole.

Similar numerals refer to similar parts 10 throughout the several figures.

Referring to the drawing, I take the heel cover 12 (Fig. 3), and place same in a suitable sewing machine and a few stitches 13 are taken through the upper edge margin of the outer sole 11 and 15 the inner edge margin of the heel cover 12 as shown in Fig. 3 to unite the heel cover 12 to the edge of the outer sole 11 about one-quarter of an inch from such heel cover edge. Then the outer edge 14 of the sole 11 is placed in line with the 20 stitching 13 and the stitching 13 is continued to the left along the outer edge 14 as shown in Fig. 3. The heel cover 12 is pulled lengthwise in the line of stitching during this stitching operation 25 to take out any fullness of the material that may be produced when the sole edge 14 is turned inwardly (Figs. 3-5) to form the finished edge on the outside of the outer sole 11 as shown in Fig. 2.

After the sole padding 10 has been cemented 30 or otherwise secured in place over the outer sole 11, the sole edge 14 is turned in against the padding 10, and then the quarter inch margin 15 of the heel cover 12 formed by the stitching 13 out of the outer margin of the heel cover 12 is cemented on top of the sole padding 10 as shown in Fig. 4.

The heel core 16 that may be a hair felt padding as shown in Fig. 5, or if a hard heel is desired, such core 16 may be made of wood to 40 preserve the even outline of the heel when the heel cover 12 is pulled over the heel and cemented thereto, is cemented or secured to the sole padding 10 and margin of the heel cover 12 as shown in Figs. 5 and 6. The outer edge of the heel 45 core 16 is preferably in substantial alignment with the rounded edge of the outer sole 11 as shown in Figs. 2, 5 and 6.

I then pull the heel cover 12 upwardly and around the heel core 16 as shown in Fig. 6, and 50 the upper margin of such heel cover 12 is then pulled over to the top of the heel core 16 and is cemented to the heel core 16 and the shank portion 17 of the slipper as shown in Fig. 7. Then the rearward extension strips 18 of the upper 55

(Figs. 1 and 7) adjacent the heel are pulled inwardly and cemented over the forward ends of the heel cover 12 to hold such ends in place and support the shank of the slipper.

5 Then the sock lining or innersole 19 is cemented over the heel cover 12 and heel core 16 as well as the extension strips 18 that are turned inwardly over the heel cover 12 and heel core 16 (Fig. 9), and the shoe is completed as shown 10 in Figs. 1 and 2.

From the foregoing description it will be noted that I have provided a novel and improved heel and sole construction for a slipper by which the heel core is protected by a cover that extends inwardly over the heel core between the sole padding and inner sole, which cover extends forwardly into the shank of the slipper and is secured in place by parts of the upper that extend over the heel cover and core to secure firm arch 15 supports with that portion of the upper to which the usual trim is fastened, and the parts of the upper are firmly bonded between the heel itself and the inner sole 19. Such heel and sole construction as hereinbefore described effectively 20 maintains the contour of the slipper and also prevents spreading or other distortion when worn, so that these factors add materially in 25 keeping the heel and sole in proper shape with correspondingly longer life in such slippers as 30 used.

I claim as my invention:

1. A shoe heel and sole construction comprising in combination an outer sole having an inwardly bent-over marginal edge to abut a sole 35 padding secured to the inner surface of the outer sole, a heel core positioned over and secured to said sole padding, a heel cover stitched to said bent-over margin of the outer sole, said heel cover enveloping the heel core, with the upper inturned marginal edge of the heel cover secured directly 40 to the top surface of the heel core and its lower margin secured directly to the marginal top surface of said sole padding, and an inner sole secured to the heel core and the inturned marginal 45 edge of the heel cover.

2. A shoe heel and sole construction comprising in combination an outer sole having an inwardly bent-over margin abutting against the outer edge of a sole padding secured to the inner 50 surface of the outer sole, a heel core positioned over and secured to said sole padding, a heel cover stitched to said bent-over margin of the outer sole, said heel cover enveloping the heel core, with the upper inturned marginal edge of 55 the heel cover secured directly to the top surface of the heel core and its lower margin secured directly to the marginal top surface of said sole padding with the outer edge of the outer sole in alinement with the outer surface 60 of the heel cover, and an inner sole secured to the heel core and the inturned marginal edge of the heel cover.

3. A shoe heel and sole construction comprising in combination an outer sole having an inwardly bent-over margin to engage a sole padding secured to the inner surface of the outer sole, a heel core positioned over and secured to said sole padding, a heel cover stitched to said bent-over margin of the outer sole, said heel 65 cover enveloping the heel core, with the upper inturned marginal edge of heel cover secured directly to the top surface of the heel core and its lower margin secured directly to the marginal top surface of said sole padding, an extension strip projecting inwardly from each side of the 70

upper cemented to subjacent portions of the heel cover to hold said heel cover portions in place and to support the shank and an inner sole secured to the heel core and the inturned marginal edge of the heel cover over said extension strip.

4. A shoe heel and sole construction comprising in combination an outer sole having an inwardly bent-over margin abutting against the outer edge of a sole padding secured to the inner surface of the outer sole, a heel core positioned over and secured to said sole padding, a heel cover stitched to said bent-over margin of the outer sole, said heel cover enveloping the heel core, with the upper inturned marginal edge of the heel cover secured directly to the top surface of the heel core and its lower margin secured directly to the marginal top surface of said sole padding with the outer edge of the outer sole in alinement with the outer surface of the heel cover, an extension strip projecting inwardly from each side of the upper cemented to subjacent portions of the heel cover to hold said heel cover portions in place and to support the shank, and an inner sole secured to the heel core and the inturned marginal edge of the heel cover over 25 said extension strip.

5. A shoe heel and sole construction comprising in combination an outer sole having an inwardly bent-over margin, the raw edge of which abuts against a sole padding cemented to the inner surface of the outer sole, a heel core positioned over and secured to said sole padding the outer surface of said heel core being in substantial alinement with the outer edge of the outer sole, a heel cover enveloping said heel core and stitched to the bent-over margin of the outer sole to provide a marginal strip inside said stitching which is cemented directly to the marginal top surface of the sole padding, with the upper inturned marginal edge of the heel cover cemented directly to the top surface of the heel core, and an inner sole cemented to the heel core and inturned marginal edge of the heel cover, the outer edge of said inner sole being in substantial alinement with the outer edges of the covered heel core and outer sole.

6. A shoe heel and sole construction comprising in combination an outer sole having an inwardly bent-over margin, the raw edge of which abuts against a sole padding cemented to the inner surface of the outer sole, a heel core positioned over and secured to said sole padding the outer surface of said heel core being in substantial alinement with the outer edge of the outer sole, a heel cover enveloping said heel core and stitched to the bent-over margin of the outer sole to provide a marginal strip inside said stitching which is cemented directly to the marginal top surface of the sole padding, with the upper inturned marginal edge of the heel cover cemented directly to the top surface of the heel core, an extension strip projecting inwardly from each side of the upper cemented to subjacent portions of the heel cover to hold said heel cover portions in place and to support the shank, and an inner sole cemented to the heel core and inturned marginal edge of the heel cover over said extension strip, the outer edge of said inner sole being in substantial alinement with the outer edges of the covered heel core and outer sole.

7. A method of making a shoe heel and sole construction which comprises stitching the lower margin of a heel cover inside the outer edge of an outer sole to provide a marginal strip extending inwardly of the stitching, then turning in- 75

wardly the outer margin of the outer sole to abut against a sole padding cemented to the inner surface of the outer sole, then cementing the marginal strip of the heel cover inside the stitching directly to the marginal top surface of the sole padding, then cementing a heel core to the top surface of the sole padding and pulling the heel cover upwardly over the heel core and cementing the upper inturned margin thereof directly to the heel core, and finally cementing an inner sole to the heel core and upper inturned margin of the heel cover.

8. A method of making a shoe heel and sole construction which comprises stitching a heel cover inside its lower edge inside the outer edge of an outer sole to provide a marginal strip extending inwardly of the stitching, then turning inwardly the outer margin of the outer sole

whereby the raw edge of the outer sole abuts against a sole padding cemented to the inner surface of the outer sole, then cementing the lower marginal strip of the heel cover inside said stitching directly to the marginal top surface of the sole padding, then cementing a heel core to the top surface of the sole padding and lower margin of the heel cover while pulling the heel cover upwardly to envelop the outer surface of the heel core, then cementing the upper inturned margin of the heel cover directly to the heel core with the forward ends of the heel cover cemented to the shank portion of the upper, and finally cementing an inner sole to the heel core, the inturned margins of the heel cover and the part 15 of the shank turned inwardly over the heel core.

JOHN E. DISCH.
